UNITED STATES PATENT OFFICE.

WALTER J. GLIDDEN, OF SOUTHBORO, MASSACHUSETTS, ASSIGNOR TO UNITED SHOE MACHINERY CORPORATION, OF PATERSON, NEW JERSEY, A CORPORATION OF NEW JERSEY.

SEWING-MACHINE.

1,342,165.

Specification of Letters Patent. Patented June 1, 1920.

Application filed June 20, 1918. Serial No. 240,961.

To all whom it may concern:

Be it known that I, WALTER J. GLIDDEN, a citizen of the United States, residing at Southboro, in the county of Worcester and 5 State of Massachusetts, have invented certain new and useful Improvements in Sewing-Machines; and I do hereby declare the following to be a full, clear, and exact description of the invention, such as will enable others skilled in the art to which it 10 pertains to make and use the same.

The present invention relates to sewing machines, and more particularly to lock-stitch, outsole, shoe sewing machines which 15 employ a curved awl and a curved hook needle.

Sewing machines of this character are provided with a presser foot, which engages the work and is locked in its work engaging 20 position during the stitch-forming operation to hold the work on the work support, and which is moved out of engagement with the work at the time the work is fed, so as not to interfere with the feeding movement.

25 The object of this invention is to provide novel and improved mechanism for actuating and locking the presser foot, by means of which the presser foot is operated to engage the work so as to clamp the work on the work support, is locked in work engaging 30 position, and is released from the work to permit the same to be fed in a more reliable and satisfactory manner than in machines as heretofore constructed.

35 With this object in view, the invention contemplates the provision in a shoe sewing machine of the class referred to having stitch-forming devices, a work support and a presser foot, of yielding means to bring 40 the presser foot into engagement with the work and at the same time permit it to accommodate itself to different thicknesses of the work, novel means for raising the presser foot during each cycle of operations through 45 a predetermined uniform distance from the position it assumes under the action of the yielding means, and novel locking means for locking the presser foot in its work engaging position.

50 An additional feature of the present in-

vention consists in the provision of means for adjusting the throw of the presser foot actuating mechanism to correspondingly adjust the lifting movement of the presser foot, adjustable means for releasing the 55 presser foot lever from its lifting mechanism at the end of the lifting movement of the latter, and means for moving the presser foot into engagement with the work when so released.

60 A further feature of the invention resides in the provision of means for lifting the presser foot, and adjustable means for releasing the lifting means from the presser foot to control the lifting movement of the 65 presser foot.

A still further feature of the invention contemplates the provision of means for releasing the presser foot lifting clutch when the parts are in normal position, so as to 70 permit the presser foot to be lifted manually without interference by the clutch mechanism.

Certain other features of the invention relate to improved constructions, combinations and arrangements of parts hereinafter 75 described and claimed, the advantages of which are set forth in the following detailed description.

In the drawings illustrating the preferred 80 embodiment of the invention, Figure 1 is a vertical longitudinal section showing the parts of the presser foot mechanism in side elevation; Fig. 2 is a sectional view of the locking device on the line 2—2 of Fig. 1, and 85 looking in the direction of the arrows; Fig. 3 is a sectional view of the locking device on the line 3—3 of Fig. 1, looking in the direction of the arrows; Fig. 4 is a detail view, in side elevation, of the clutch device 90 for lifting the presser foot lever.

In the machine illustrated in the drawings, the work is supported between a work support 2 and the presser foot 4. The work support is of the usual construction, being 95 secured to a stationary part of the machine frame and being formed to enter the crease between the upper and the welt of a shoe so that the shoe, during the sewing operation, is supported with the tread surface of the 100

sole uppermost. The work support is provided with the usual slot through which the needle and awl operate.

The presser foot is of the usual construction and is secured to the lower end of a presser foot lever 6. During the greater part of the cycle of operations of the machine, the presser foot is held firmly locked against the work, so that the work is tightly clamped between the presser foot and the work support. During the feeding of the work, however, the presser foot is normally raised from the work so as to offer no resistance to the feeding movement. At the end of the feeding movement, the presser foot is released and is pressed yieldingly against the work, so that it has opportunity to accommodate itself to the thickness of the stock. After being pressed yieldingly against the work, the presser foot is locked in work engaging position and remains locked until just before the beginning of the feeding operation, when it is again lifted and the cycle of operations repeated.

To enable the presser foot to be actuated as above described, the presser foot is pivotally mounted on a stud 8 fixed in the machine, and has a downwardly extending arm 10 to which is secured at its lower end by means of a pin 11, a curved arm 12, the function of which will be more particularly described hereinafter, and to which is pivotally connected a link 14 connected at its rear end to an arm 16 secured to a rock shaft 18. A spring 20 is connected between the link 14 and an arm 22 secured to a rod 24 by a split clamp 26, by means of which the position of said arm on the rod 24 may be adjusted so as to vary the tension of the spring 20. Normally, this spring tends to pull the link 14 rearwardly, and, by means of the connections above described, to move the presser foot downwardly to yieldingly engage the work. Also, by means of the rock shaft 18 and the usual connections, the spring 20 operates the thread measuring device in the well-known manner.

To lift the presser foot to disengage it from the work during the feeding movement, mechanism is provided consisting of an arm or lever 28 pivotally mounted on the stud 8 and carrying at its lower end a clutch or gripping device to grip the extending arm 12 when the lever 28 is positively actuated by the driving shaft A. The lever is actuated by a link 32 pivotally connected at one end to a stud 30 secured in the lever 28, and adjustably connected at the other end in a slot 34 formed in the lower end of the cam lever 36 pivoted on a fixed stud 38 and carrying a roll 40 at its upper end which engages in a groove in the vertical face of a disk cam B secured to the main shaft A. The lever 36 is positively oscillated on its pivot when the main shaft

is rotated, and when so oscillated rocks the lever 28 on its pivot. As the arm 28 is rocked, the presser foot is positively lifted by means of the clutch device above referred to, which engages the arm 12 connected to the presser foot lever.

The clutch device comprises a plate 42, secured by means of a screw 44 to the lower end of the lever 28. This plate is arranged within the inner surface of the arcuate arm 12. The plate 42 is so designed as to form a recess between its inner face and the arm 12, in which is received a roll 48 which is confined between a projecting portion of the plate 42 and a latch lever 52 pivotally mounted on the plate 42, as shown in Fig. 4. The recess in the plate 42 is so designed that the roll 48, when in one end of said recess, is free to turn without engaging the arm 12. If, however, the roll is moved toward the other end of said recess, it will be jammed between the surfaces of the plate 42 and the arm 12, and will enable the lever 28 to positively move the arm 12 and to lift the presser foot off the work. A spring 50 normally tends to move the roll 48 to its clutching position. The clutch roll 48 is held against lateral displacement in the recess between the lever 28 and the cover plate 29.

The link 32 is adjustably connected in the slot 34 in order that the lifting movement of the presser foot lifting lever 28 may be adjusted to suit the requirements of the different materials which may be operated upon. The link 32 and the lever arm 36 constitute the members of a toggle linkage. When the link 32 is connected in the rear end of the slot 34, as shown in Fig. 1, the lever 28 will be given a greater lifting movement, on oscillation of the lever 36, than it would if the link were connected at a point intermediate the ends of the slot 34. When the lever 28 is in its normal rearmost position, with the presser foot down on the work, the latch lever 52 engages an abutment 53 which swings the latch lever about its pivot, thus moving the roll 48 forwardly into the enlarged end of the recess in the plate 42 so as to prevent the engagement of the clutch device with the arm 12, for a purpose hereinafter fully set forth. When the arm 36 is in its normal position, as shown in Fig. 1, the slot 34 is concentric to the pivot point of the link 32, so that a change of the adjustment of the link 32 in said slot does not change the position of the lever 28, and in no way interferes with the proper action of the clutch device.

Devices are provided to release the clutch device when the presser foot is raised out of engagement with the work, through such a distance as desired, in order to permit the actuating spring 20 to pull the presser foot down into engagement with the work while the presser foot is entirely free to move.

These devices comprise a spring-pressed plunger 54 engaging the latch lever 52 and held in such a position by its spring, during the swinging movement of the lever 28, that the latch lever 52 occupies the position shown in Fig. 4, with the clutch roll in its clutching position. As the lever 28 is moved forwardly, however, the plunger 54 is adapted to strike against an adjustable abutment screw 56 in an upstanding arm of a bracket 64 secured to the machine frame and is pushed rearwardly by said screw. This movement of the plunger operates the latch lever 52 to move the clutch roll 48 to ineffective position. By adjusting the screw 56, the time of the release of the clutch device may be adjusted. The screw 56 is normally adjusted in accordance with the adjustment of the link 32 in the slot 34, so as to release the clutch device at the completion of the lifting movement of the lever 28. When the adjustment of the link 32 in the slot 34 is changed, the adjustment of this screw 56 is normally changed so as to correspond to that of the link 32. The screw 56 may be so adjusted, however, that it controls the lifting of the presser foot by the lever 28. If, for instance, the link 32 is so adjusted in the slot 34 that the lever 28 is given its maximum lifting movement, the screw 56 may be so adjusted that it will release the clutch device from the arm 12 before the lever 28 has completed its lifting movement. If such an adjustment of the screw 56 is made, a part of the lifting movement of the lever 28 is idle, with respect to the presser foot, and the lifting of the presser foot is controlled entirely by the adjustment of the screw 56.

At a certain period in each cycle of operations, the arm 12 is locked against movement by a locking device, described in detail hereinafter, which prevents any movement of the presser foot at this time. The arm 12 is unlocked slightly before the feeding movement to permit the presser foot 4 to be lifted off of the work, as above described, and is locked against movement subsequent to the feeding action and just after the spring 20 has drawn the presser foot down into engagement with the work. The mechanism for positively locking the arm 12 against movement comprises a short curved arm 60 pivoted on the rear end of the arm 12 and having the same degree of curvature as said arm. The arm 12 slides in a guideway formed in the fixed bracket 64, and fits closely in said recess so as to have no lost motion therein and to move in a fixed path, while the short arm 60 slides endwise through a guideway carried by the locking member 62, which is mounted to slide in a slide-guide formed in the bracket 64 and in a direction substantially radial

to the arc of the curvature of the arm 12. When the locking member is in its ineffective position, the curved arm 60 is in exact alinement with the arm 12, and the arms are free to slide endwise in the guideways. 70 When the locking member 62 is moved rearwardly, the arm 60 is moved out of alinement with the arm 12, and when said arm occupies such position, any attempt to move the arm 12 longitudinally will cause the 75 arm 60 to jam in the guideway through which said arm passes.

The guideway for the arm 60 is formed in a locking nut 66 and when the locking member 62 is moved rearwardly, the arm 80 12 is also clamped between said locking nut and the bracket 64. The locking nut 66 has threaded engagement with the locking member 62 by means of a very steep thread, as clearly illustrated in Fig. 2. By 85 reason of the engagement of the arm 60 with the nut 66, said nut is turned in the locking member 62 when the arm 60 is swung on its pivot, and by means of the steep thread on said nut it is moved toward 90 the arm 12, a small space being provided between the inner face of the nut and the arm 12 to permit this movement of said nut. As the locking nut is moved toward 95 the arm 12, it clamps the arm 60 against the arm 12, and thus clamps the arm 12 against the face of the bracket 64 in which said arm slides. The locking member is adapted to be moved to lock the arm 12 in various positions of said arm, the position of the arm at the time of operation of the locking member depending upon the thickness of the work. Since the short arm 60 is pivoted at its upper end, different parts of said arm are moved through different distances when the locking member is moved rearwardly. The locking nut 66 is therefore turned through different distances by the arm 60, depending upon the relative position of the arm 12 and locking member 62, when the locking member is moved to locking position. It is desirable to exert the same clamping pressure on the arm 12 by means of the locking member 62, in whatever position said arm may be when the locking member becomes ineffective. The arm 60 is therefore made thicker at its upper end than at its lower end, so that the smaller movement of the upper path of said arm will cause the locking nut 66 to exert the same clamping action as the greater movement of its lower end. 110

The arm 60 is likely to wear in continually sliding back and forth through the nut 66, 125 and in order to take up this wear, the arm 60 is formed in two parts, indicated in Fig. 2 as 60^a and 60^b. Projecting from the side of the part 60^b are pins 70 which extend in recesses formed in the part 60^a and on which 130

said part is removably mounted. The part 60^a may be removed by the operator and one or more very thin plates 74 placed between the parts 60^a and 60^b, the number of plates 5 depending on the wear of the parts.

The mechanism for operating the locking member comprises a link 78 connected to the locking member by means of a stud 76 rotatably mounted therein. This link is connected to the forward end of a rock arm secured to the rock shaft 82, journaled for rotation in the frame of the machine. Adjustably secured to the shaft 82 by means of a split clamp is an arm 84, having connected 10 at its rear end a depending rod 86 surrounded by a compression spring 88, which normally tends to raise the arm 84 and rock the shaft 82 to pull the link 78 rearwardly and move the locking member to locking position. The locking member 62 is, however, held in its forward or unlocking position during a certain period of each cycle of operations, by means of an upstanding arm 90 pivoted on the rock shaft 82 and having 15 adjustably mounted on its upper end a roll 92 which engages in a cam groove formed in the vertical face of the cam B. The cam operates to rock the arm 90 on the shaft 82, and on the rearward movement of said arm 20 it engages a short arm 94 secured to said shaft and rocks the shaft 82 so as to move the locking member 62 to unlocking position, where it is held so long as the arm 90 remains in its rearward position.

Mechanism is provided by means of which the presser foot may be manually raised to its disengaging position, and at the same time the locking device may be moved to ineffective or unlocking position. Such mechanism consists of a rod 96 extending longitudinally of the machine, at its forward end passing through a recess in the upstanding arm 98 secured to the presser foot lever, and at its rear end connected to an upstanding arm 100 secured to a rock shaft 102 and normally held in forward position by means of a tension spring 104. A nut 106 is secured to the forward end of the rod 96, and when said rod is moved rearwardly, the nut 35 engages and moves rearwardly the arm 98, positively lifting the presser foot off the work. The rod 96 in moving rearwardly also rocks the arm 100 and swings forwardly a downwardly extending arm 108 integral 40 with the arm 100. The arm 108 has at its lower end a lateral projection 110 in the form of a cam which engages a roll 112 mounted on an arm 114 secured to the rock shaft 82, and rocks the shaft 82 to move 45 the locking member 62 to ineffective position on the rearward movement of the rod 96. The cam 110 is so formed that the forward portion of said cam is effective to move the arm 114 to rock the shaft 82, while the 50 rear portion of the cam is substantially con-

centric with the pivot 102 and acts to hold the locking mechanism in ineffective position. There is a certain amount of lost motion between the collar 106 and the arm 98 to permit the cam 110 to rock the shaft and release the locking device before the collar strikes the arm 98 to lift the presser foot off the work. After the presser foot is lifted, and during the continued rearward movement of the rod 96, the locking member is 55 held in its ineffective position by the concentric portion of the cam 110. When the presser foot is descending, on release of the rod 96, the concentric portion of the cam 110 holds the locking device in ineffective 60 position until the presser foot is engaged with the work. As hereinbefore set forth, the clutch device is held in such position that it cannot grip the arm 12 when the lifting arm 28 is in its normal position. The clutch 65 device is held open when the parts are in normal position, so as to enable the arm 12 to move to its normal position after the presser foot is lifted manually. If the clutch were not released, the arm 12 would be 70 gripped by the clutch device, preventing the presser foot from dropping into engagement with the work after it had been lifted from the work by the action of the rod 96. The rod 96 has a knob or handle at its forward end in such position as to be conveniently grasped by the operator so that he may lift the presser foot when it is desired 75 to remove the work for any purpose. When the rod 96 is released by the operator, the spring 104 restores the parts to normal position. Means are provided, as indicated at 80 116, for adjusting the length of the rod 96.

The nature and scope of the present invention having been indicated and its preferred embodiment having been specifically described, what is claimed as new is:—

1. A sewing machine having, in combination, stitch-forming devices, a work support, a presser foot, mechanism for actuating the presser foot, comprising a presser foot lever, an arm extending therefrom, a pivoted lever, a clutch device carried by said lever and engaging said arm, and means for actuating said pivoted lever to raise the presser foot 110 from the work.

2. A sewing machine having, in combination, stitch-forming devices, a work support, a presser foot, mechanism for actuating the presser foot, comprising a presser foot lever, an arm extending therefrom, a pivoted lever, a clutch device carried by said lever and engaging said arm, means for actuating said pivoted lever to raise said presser foot, and means operating to release said clutch 120 device at the completion of the upward movement of the presser foot.

3. A sewing machine having, in combination, stitch-forming devices, a work engaging device, a member movable in a fixed 125

path connected thereto, an arm pivoted to said member and movable endwise thereby, a movable guideway for said arm, and means for holding said guideway in fixed 5 position out of alinement with said fixed path.

4. A sewing machine having, in combination, stitch-forming devices, a work engaging device, a member movable in a fixed 10 path connected thereto, an arm pivoted to said member and movable endwise thereby, a movable guideway for said arm, and means for moving said guideway into and out of alinement with said fixed path.

15 5. A sewing machine having, in combination, stitch-forming devices, a work support, a presser foot, mechanism for actuating and locking the presser foot, comprising a pivoted lever secured to the presser foot, an 20 arm extending therefrom, a second arm pivoted on said extending arm, a locking member having a recess therein embracing said pivoted arm, a nut threaded in said locking member and having a recess through which 25 said pivoted arm passes, and means for actuating said locking member to swing said arm on its pivot, whereby said nut is moved to lock said extending arm against movement.

30 6. A sewing machine having, in combination, stitch-forming devices, a work support, a presser foot, mechanism for actuating and locking said presser foot, comprising a pivoted lever, an arm extending from said 35 lever, a second arm pivoted thereon and normally alined therewith, a locking member having a recess embracing said pivoted arm, and means for actuating said locking member to move said pivoted arm out of alinement with said extending arm.

40 7. A sewing machine having, in combination, stitch-forming devices, a work support, a presser foot, mechanism for actuating and locking said presser foot, comprising a pivoted lever, a curved arm extending from said lever, a second arm having the same degree of curvature as said extending arm, pivoted thereon and normally alined therewith, a locking member having a recess embracing said pivoted arm, means for actuating said locking member to move said pivoted arm out of alinement with said extending arm whereby said arm is jammed against longitudinal movement, and a nut threaded 50 in a recess in said locking member and having a recess through which said pivoted arm passes, said nut being actuated by the movement of the pivoted arm to clamp said extending arm in position.

60 8. A sewing machine having, in combination, stitch-forming devices, a work support, a presser foot, mechanism for actuating and locking said presser foot, comprising a pivoted lever, an arm extending therefrom, 65 clutch devices gripping said arm, means for

actuating said clutch devices to operate the presser foot, locking mechanism, and means for actuating said locking mechanism to engage and positively lock said extending arm against movement.

70 9. A sewing machine having, in combination, stitch-forming devices, a work support, a presser foot, mechanism for actuating the presser foot comprising a presser foot lever, an arm extending therefrom, a clutch device 75 engaging said arm, means for operating the clutch device to lift the presser foot, and means for releasing the clutch device from said arm at the end of the lifting movement of the presser foot.

80 10. A sewing machine having, in combination, stitch forming devices, a work support, a presser foot, mechanism for actuating the presser foot comprising a presser foot lever, an arm extending therefrom, a clutch device 85 engaging said arm, means for operating the clutch device to lift the presser foot, and adjustable means for releasing the clutch device from said arm, to adjust the lifting movement of the presser foot.

90 11. A sewing machine having, in combination, stitch-forming devices, a work support, a presser foot, mechanism for actuating the presser foot comprising a presser foot lever, means for operating the lever to lift 95 the presser foot, connections between said lever and the operating means, and adjustable means for releasing said connections to control the lifting movement of the presser foot.

100 12. A sewing machine having, in combination, stitch-forming devices, a work support, a presser foot, mechanism for operating the presser foot, comprising a presser foot lever, means for operating the lever to lift the 105 presser foot, means for adjusting the movement of said operating means to control the lifting movement of the presser foot, connections between the presser foot lever and said operating means, and adjustable 110 means for releasing the connections between the operating means and the presser foot lever.

115 13. A sewing machine having, in combination, stitch-forming devices, a work support, a presser foot, mechanism for actuating said presser foot comprising a presser foot lever, an arm extending therefrom, a pivoted lever, a clutch device carried by said lever and engaging said arm, means for actuating said 120 pivoted lever to lift the presser foot, adjustable means for controlling the lifting movement of said lever, and adjustable means for releasing the clutch device at the end of the lifting movement of said lever.

125 14. A sewing machine having, in combination, stitch-forming devices, a work support, a presser foot, mechanism for actuating the presser foot, comprising a presser foot lever, an arm connected to said presser foot lever,

a pivoted lever, a clutch carried by said pivoted lever and engaging said arm, means for actuating said pivoted lever to lift the presser foot, and means for releasing said clutch from said arm when said pivoted lever is in normal position.

15. A sewing machine having, in combination, stitch-forming devices, a work support, a presser foot, mechanism for actuating the

presser foot, comprising a presser foot lever, 10 an arm connected to said presser foot lever, means engaging said arm to lock the presser foot in work engaging position, means for releasing said locking means, and means engaging said arm to lift the presser foot off 15 the work.

WALTER J. GLIDDEN.
